COMBINED CAN LID AND STACKING GUIDE

Jim W. Borum, East Gary, Ind.
(819 Elkhart St., Gary, Ind. 46403)

Filed June 12, 1975, Ser. No. 586,301

Term of patent 14 years

Int. Cl. D9—07

U.S. Cl. D9—254

Fig. 1

Fig. 2

Fig. 3

Fig. 4

FIG. 1 is a top plan view of a combined can lid and stacking guide embodying my new design;

FIG. 2 is a side elevational view;

FIG. 3 is a bottom plan view; and

FIG. 4 is an enlarged, fragmentary cross-sectional view taken on the line 4—4 of FIG. 1.

I claim:

The ornamental design for a combined can lid and stacking guide, substantially as shown.
